MACHINE FOR APPLYING A WEB TO A
STEAND

Charles B. Fantone, Lyndhurst, and Edward G. Parvin, Roselle, N. J., assignors to Syncro Machine Company, Newark, N. J., a corporation of New Jersey

Application August 23, 1934, Serial No. 741,046

19 Claims. (Cl. 117—42)

This invention relates to improvements in machines of the type employed for wrapping a narrow web or tape of insulating or similar material about a longitudinally moving strand or cord in the form of a helical rod composed of abutting or overlapping turns.

One of the objects of the invention is to provide an improved and automatic form of brake for the cop and cop spindle of such machines which acts to immediately bring the cop to a dead stop when the web breaks.

A further object of the invention is to provide in conjunction with the above mentioned brake a brake for the serving head upon which the cop is mounted to likewise bring it to a dead stop when the web breaks.

A further object of this invention is to provide an automatic switch which operates to closed position when the web breaks to stop the machine and energize both of said brakes.

These and many other objects, as will appear from the following disclosure are secured by means of the structure which comprises this invention.

This invention resides substantially in the combination, construction, arrangement and relative location of parts, all as will be fully described below.

In the drawings,

Fig. 1 is a vertical, central, cross sectional view of a serving head to which the herein disclosed invention is applied, showing some parts in elevation;

Fig. 2 is a top plan view thereof with some parts broken away;

Fig. 3 is a cross sectional view through the commutator;

Fig. 4 is an enlarged vertical, central, cross sectional view through the cop spindle showing the automatic cop spindle brake in elevation;

Fig. 5 is a top plan view of the automatic switch and cop spindle brake showing the shaft in cross section;

Fig. 6 is a cross sectional view taken on the line 6—6 of Fig. 5;

Fig. 7 is a cross sectional view taken on the line 7—7 of Fig. 5;

Fig. 8 is a diagrammatic view of the circuit connections for a complete machine of which the serving head is a part, and shows the connection of the various parts in a system in which both commutator rings of the serving head are employed;

Fig. 9 is a diagrammatic view of the circuit connections of the portion of the circuit of Fig. 8

modified to show an arrangement in which only one commutator ring is employed;

Fig. 10 is a further modification employing but a single commutator ring.

The present invention represents an improvement of a portion of the machine shown in the copending application of Fantone and Jameson, Serial No. 702,520, filed December 15, 1933. The structure herein disclosed is concerned particularly with improvements in the serving head of a machine such as that disclosed in the above mentioned copending application. The general electric circuit arrangements as employed with the apparatus of which the structure of this case is an improvement is similar to that disclosed in the above mentioned copending application and is shown in this case with the modifications which adapt it for use with the improved serving head structure about to be described.

The standard or bracket 1 which supports the serving head is to be attached to the main standard of the machine in proper position and has secured thereto in any suitable way the serving head motor 2. This motor is provided with a shaft 3 which has a central passage extending entirely therethrough through which the strand or wire W passes longitudinally. Secured to the shaft 3 at the upper end of the motor is the bearing member 4 which is journaled in the casing 5 forming a part of the upper end plate and the motor, as illustrated. The casing 5 extends into a radial platform or vertically extending wall at its periphery. The rotatable base plate 7 in the general form of a disc is provided with a central depending hub 8. This base plate is secured to the bearing member 4, which rotating with the shaft 3, causes conjoint rotation of the base plate. The depending hub 8 is provided with an insulating ring 9 on its periphery upon which in turn are mounted the continuous commutator rings 10 and 11. Ring 11 is engaged by a brush 13 which is slidably mounted in a brush holder tube 12. Mounted upon the plate 6 in suitable supports, as shown, so as to insulate it therefrom within the tube, is a spring 14 bearing upon the brush 13 to urge it into contact with the commutator ring 11, and held in place by means of a removable insulating screw cap 15. In a similar way a brush 16 for the commutator ring 10 is mounted at the opposite side of the machine.

Supported upon the base plate 7 with an angular displacement of 90 degrees are the four rotatable guides 17 which are commonly used with serving heads of this type. The base plate 7 is provided with a central cavity 18 opening from

the top thereof and preferably of circular cross section. Within this cavity, and mounted upon shaft 3, is a cylindrical cup shaped iron or steel casing 19. This casing is keyed to the shaft 3 for rotation therewith, but is slidably mounted thereon. Springs 19' are interposed between the bottom of the cavity and the bottom of the casing 19 so as to form a resilient seat therefor. Within the casing 19 is an annular member 20 having a central upstanding circular ridge 21 with a rounded top edge, as is clear from Fig. 6. The ring-like member 20 is rotatably journaled in the casing 19 on the ball bearing 21. Fitting snugly within the inner wall of the casing 19 is a ring shaped magnetizable winding 22.

The ring like member 20 is connected to the casing 19 by means of a coil spring 23 having its lower end in a slot in the casing (see Fig. 6), and having its upper end in a slot in the ring-like member 20. Thus the member 20 is locked to the casing 19 and the shaft 3 but is permitted some relative movement with respect thereto through this spring connection.

Mounted between the winding 22 and the member 20 is a bracket 26 having an adjustable stop screw 25 locked thereon. This stop screw is positioned to engage an arm 24 secured to the member 20 and having a depending lip for engagement with the stop screw. Upon the other side of the ring 20 is secured another arm 28 having a contact secured thereto. This contact is positioned so as to engage a fixed contact 29 mounted in a bracket 30 and insulated therefrom, which bracket is secured to the casing 19. The spring 23 is so arranged that normally it causes the member 20 to rotate on its bearing so as to engage the contact on the arm 20 with contact 29. Secured diametrically opposite to each other in the casing 19, are a pair of brackets 31 which have lips overlying the ring member 20 so as to hold it from moving longitudinally on the shaft 3.

As has been clearly shown in Fig. 4 there is mounted upon the shaft 3 towards its upper end, by means of roller bearings 34 and 35, the cop spindle 32. Such spindles are commonly used in serving heads of this type, and are constructed to receive the cord or spool of tape to be wrapped around the string or wire. Secured to the lower end of the cop spindle is an iron or steel disc 33 positioned not only to engage the rounded edge of the ridge 21, but when in such engagement to be in close proximity to the rim of the cup shaped member 19. The upper end of the cop spindle is engaged by a ball bearing 37 which is applied under the proper pressure to the end thereof by means of a vertically adjustable hand nut 36. Thus the pressure of the cop spindle and casing 19 with all of its parts upon the springs 19' may be properly adjusted to space the web from the cop under proper tension as it is fed therefrom. The upper end of shaft 3 is longitudinally slotted and tapered and is threadedly engaged by an adjustable nut 40 which is internally tapered. By means of this locking arrangement the guide die 38 may be locked in place. This die has a smaller bore through the center thereof for guiding the wire or string therethrough. Secured to the guide die 39 is the nose piece 41 upon which in turn is mounted the nose guide 42. Both of these parts are likewise commonly used with devices of this type.

The rotatable base plate 1 is provided with a peripheral rabbet forming a depending flange 1' of cylindrical cross section which is engaged by the brake bands 43 and 44, which are pivotally

secured to the flange of the fixed plate 6, as indicated at 45 and 46 respectively (see Fig. 2). These brake bands may support the usual brake lining as indicated, and are provided at their free ends with projecting ends as is clear from the figures. These ends are interconnected by means of a bolt 47 having mounted thereon so as to engage the outer faces of the ends, the springs 48. Secured to the flange of the plate 6 is a bracket 47 upon which rests a spring 51 which encircles the vertically movable rod 49. This rod is provided with a cam member 52 which lies between the end side faces of the extensions and the brake bands. The lower end of rod 49 is pivotally connected to the armature 54. This armature is pivotally supported upon a steel bracket 55 which forms a part of the core for the electro-magnet 56. As will be apparent, when the electro-magnet is energized the armature will be pulled down carrying with it rod 49 and cam 52. The cam will be forced between the projecting ends of the brake bands forcing them apart and releasing the brake. Whenever the electro-magnet is deenergized spring 51 will draw the armature, rod and cam upwardly and permit the springs 48 to apply the brakes to the rotatable base plate 1.

A complete circuit arrangement for the apparatus will now be described in detail. The complete machine as illustrated in the above mentioned application, modified to the extent of employing the serving head of this application is illustrated in Figs. 1 to 7 inclusive. The feature of the circuit diagram about to be described, and illustrated in Fig. 8 is that two commutator rings are employed on the serving head as illustrated in Fig. 1 with circuit connections such that the brake coil is energized every time the machine is shut down either by the automatic stop switch, or by a manual stop button. The main power supply is illustrated as a three phase alternating current circuit represented by the supply mains 60. At 61 is the main control switch by means of which the entire apparatus may be disconnected from the power source. The wires 60 also extend through a second control switch 62 which is operated to energize and de-energize the take-up motor 63. As illustrated in the above mentioned application, the take-up motor is employed to operate the take-up reel upon which the finished product is wound. When switches 61 and 62 are closed the motor 63 is directly energized for operation at a speed determined by the adjustment of the rheostats 109 connected to the rotor circuit of that motor by the wires 108. Wires 60 are connected by wires 64 to the stator or field winding of the motor 65 which is directly connected to an alternating current generator and to the capstan wheel, in accordance with the disclosure in the above mentioned application. 66 diagrammatically represents the generator operated by the motor 65.

The rotor of the motor 65 is connected by the wires 67 to the resistances 68, which in turn are connected by the wires 69 and 71 to one contact 65 of each of the two upper pairs of the relay 70. The corresponding contacts are connected together and by wire 72 to the three resistances 68. These resistances are connected in a potentiometer circuit, and are provided with the variable tap connections 73, 74 and 75, each of which is connected to one of the resistances 78. These wires are respectively connected by the wires 79, 81 and 82 to the contacts of the relay 80, as illustrated. The other ends of resistances 78 are 75

connected by the wires 83, 85 and 86 to the contacts of relay 84 as illustrated. At 87 and 88 are electric time clocks which operate the switches 93 and 92, respectively. These time clocks are 5 of any one of a number of well known forms, and are of the type which may be set to operate for a predetermined period of time at the end of which the switches which are a part thereof close.

One terminal of the operating solenoid of relay 70 is connected by wire 76 to one terminal of the solenoid of relay 80, one terminal of the solenoid of relay 84, one terminal of the time clock 87, one terminal of the time clock 88, and to wire 77, which is connected to one terminal of 10 the brake solenoid 56, and to one terminal of the secondary 102 of the transformer 100.

The other terminal of the solenoid of relay 70 is connected by wire 89 to one contact of the start switch 90 and to wire 91 which interconnects the other terminal of the brake solenoid 56 with one terminal of each of the switches 92 and 93 of the time clocks. Wire 91 is also connected to the other terminal of the time clock 88. The other terminal of the solenoid of relay 80 is 15 connected by wire 94 to the other contact of switch 93, and the other terminal of the solenoid of relay 84 is connected by wire 95 to the other contact of switch 92, and to the other terminal of the time clock 87. One terminal of the normally closed stop switch 98 is connected by wire 99 to one contact of the second highest pair of 20 relay 70. The corresponding contact is connected by wire 59 to wire 89. The remaining contacts of switches 90 and 98 are connected by a common 25 wire 96 to one contact of the relay 97. The other contact of this relay is connected to the other terminal of secondary 102. Another secondary 30 103 of the transformer 101 has one terminal grounded and is connected at its other terminal by wire 104 to the solenoid of relay 97, which in turn has its other terminal connected by wire 105 to the brush of ring 11. The primary of the transformer 101 is connected through wire 100 to one phase of the main current supply. The brush of ring 10 is connected by wire 106 to one 35 of the contacts of the lowest pair of relays 70. The corresponding contact is connected by wire 107 to wire 104. It is noted that relays 70, 80, 40 84 and 97 are shown in deenergized position.

The stator or field winding 111 of the generator 66 is connected by the wires 110 to the main current source. This winding is of course a three-phase winding. One of the terminals is connected by wire 113 directly to one terminal 45 of the three-phase field winding 114 of the serving head motor 2. The other terminals of the field winding 111 are connected by the wires 112 to the reversing switch 115, and through it by wires 116 to the remaining terminals of the field 50 114. In a similar manner the rotor windings of the generator are connected by wire 117 to one terminal of the three-phase rotor winding of the serving head motor 2, and by wires 118 through 55 the reversing switch and wires 119 to the other terminals of the serving head rotor.

The operation of this circuit will now be described. The reversing switch 115 is at either of its two positions, depending upon the desired direction of rotation of the serving head. The 60 value of this feature is that where two or more layers of insulation are applied to a wire in a spiral wrap it is desirable to have adjacent layers wound in opposite directions, which is accomplished by reversing the direction of rotation of 65 the serving head rotor.

The parts in Fig. 8 are all shown in completely deenergized position, switch 61 being open. The stop switch 28 is of course normally open when there is tension on the tape or web which is to be wound around the wire, as will be apparent from the above description of the automatic stop switch.

5

When the switch 61 is closed the fields of the motor 65 and the generator 66 are energized and the primary of transformer 101 is energized. To 10 start the machine up switch 62 is closed, thereby energizing the take-up motor 63. Start switch 90 is closed, with the result that current flows from secondary 102 through relay 97, wire 96, switch 90, wire 89, the solenoid of relay 70, wire 15 76, the operating winding of time clock 88, and by wire 77 back to the other terminal of the secondary 102. Current also flows from wire 76 to the brake solenoid 56 by way of wire 91 and wire 77 to the secondary 102. The time clock 20 88 has been set to close the switch 92 at the end of a predetermined period of time for a purpose to be described. The switches controlled by the relay 70 will be closed and the brake solenoid will remain energized through switch 25 98, wire 89, switch of relay 70, wire 59, and wire 89 to wire 91 thereby releasing the brake on the serving head and a holding circuit for relay 70 is thus completed also. The operation of the relay 70 will interconnect the left hand ends of 30 resistances 68 to a common point, as will be apparent through the two upper pairs of contacts of this relay. The circuit to the spindle brake coil 22 will be broken at the lowest pair of contacts of relay 70. Thus only a 35 momentary closure of switch 90 is necessary.

Until switch 92 closes the resistance in the rotor circuit of motor 65 is the resistance 68 which is the maximum amount. Motor 65 will then begin to operate and will pick up to a 40 speed corresponding to that amount of resistance in its rotor circuit when time switch 92 is closed by the time clock 88 at the end of the period for which it is set the circuit to the solenoid of relay 84 is closed and the operating winding of 45 time switch 87 is energized, starting it. Energization of relay 84 closes its switches putting a short circuit on the right hand end of resistors 78. The resistance in the rotor circuit of motor 65 is that of resistors 78 plus the resistance of 50 the portions of resistors 68 to the right of adjustable taps 73, 74 and 75. The resistance of resistors 78 is less than that of resistors 68. The motor therefor continues to pick up speed until the end of a predetermined period, when the time 55 clock 87 closes the switch 93. Relay 80 is thus energized, having a short circuit across the left hand ends of resistors 78. The result is that the resistance in the rotor circuit is that of the portions of resistors 68 to the right of taps 60 73, 74 and 75 which is a less amount than that represented by the previous set of connections. The motor thus comes up to final and operating speed. The instant the generator 66 begins to operate the serving head motor too begins to 65 operate, its winding being energized from the generator in an obvious manner. The apparatus then continues to operate until the stop switch 98 is opened. When this occurs the holding circuit for the relay 70 through wire 99 is broken, 70 thus opening the rotor circuit of the motor 65.

At the same time a circuit for the cop spindle brake coil 22 is made from the secondary 103 through wire 107, the lowest pair of contacts of relay 70, wire 106, commutator ring 110, and 75

thence through the brake winding 22 to ground. This immediately brings the cop spindle to a stop, preventing it from overrunning, and thus preventing an undesirable unwinding of the tape on the cop spindle. At the same time that the holding circuit for the relay 70 is broken the circuit for the brake solenoid 56 is broken, so that the brake bands 43 and 44 (Fig. 2) may bring the serving head to a quick stop.

- 10 These same operations will occur automatically if the web T breaks. When this web breaks switch 28 will close in accordance with the structure thereof as described in connection with Figs. 5, 6 and 7, so that a circuit to the operating 15 solenoid of relay 97 is made through wire 105, wire 104 and the secondary 103. When this happens the relay opens again, breaking the holding circuit for relay 70, and breaking the circuit for the brake solenoid 56. Thus the arrangement 20 just described effects automatic stopping of the apparatus and prevents overrunning of the cop spindle whether the machine is brought to a stop in the normal way by opening the stop switch 98, or whether it is brought to a stop in an emergency operation when the tape breaks or the 25 tension thereof is reduced at any time sufficiently to permit the switch 28 to close.

A modification of this circuit in part is illustrated in Fig. 9 to show the connections necessary when only one commutator ring is employed 30 on the serving head. With this arrangement the brake coil for the cop spindle will only be energized when the machine is stopped by the automatic switch, and will not be energized when 35 the stop switch is opened. Only that portion of the main circuit of Fig. 8 is herein illustrated to bring out the change in connections involved, although of course the circuit of Fig. 9 is only a 40 part of the entire system. In some cases the same reference numerals have been used to indicate the same parts. The main power supply is shown at 60 as before, and the main switch is shown at 61. The wires 60 each go to one contact of the three upper pairs of the relay 70. 45 The corresponding contacts are connected by the wires 132 to the field of the motor 65. The rotor circuit in this case is illustrated with adjustable resistances 68 therein, it being apparent, however, that the potentiometer arrangement of interconnected relays and time clock switches may be employed to effect automatic 50 starting of this motor. The arrangement of Fig. 9 is a manual equivalent thereof in which the amount of resistance is gradually cut into 55 the rotor circuit manually. The primary of the transformer 136 is energized from one phase of the main circuit by the wires 135. One terminal of the solenoid of relay 70 is connected by wire 134 to one of the wires 60 and the other 60 terminal is connected by wire 133 to wire 137, which interconnects one contact of the start switch 99 with one of the contacts of the lowest pair of the relay 70.

One contact of the stop switch 98 is connected 65 by wire 138 to one of the contacts of the normally closed relay 97. The other contact is connected by wire 139 to the other contact of the lowest pair of relays 70. The other two contacts of the switches 99 and 98 are connected 70 by a common wire to one of the wires 135. One terminal of the solenoid of relay 70 is connected to ground through the secondary of transformer 136 and the other terminal is connected by wire 140 to the brush of the commutator ring 10. 75 With this arrangement, when switch 61 is closed

the primary of transformer 136 is energized. To energize relay 70 start switch 99 is closed, current flows from the current source through switch 99, wire 137, wire 133, the solenoid of relay 70 and wire 134 back to the current source. A holding circuit for the relay is then made through stop switch 98, the switch of relay 97, wire 139, the lowest pair of contacts of relay 70 and wires 137 and 133.

To stop the machine in normal operation it is 10 only necessary to open switch 98, thereby opening the holding circuit and deenergizing relay 70. However, the cop spindle brake coil 22 is not energized. If when the machine is running the tape or web being fed from the cop breaks, switch 15 28 closes completing a circuit that is quite apparent through wire 140 to energize relay 97 so that it breaks the holding circuit for relay 70. At the same time the brake coil 22 is energized, thereby bringing the cop spindle to a quick stop. 20

In the modification of Fig. 10 but one commutator ring is again used in which arrangement the cop spindle brake coil 22 will be energized when the machine is stopped by the stop button 98, or by the closing of the automatic stop 25 switch 28. In this arrangement the main circuit wires 60 are again connected through a control switch 61 to the field of the motor 65. The primary of the transformer 136 is connected by wires 135 to the current source. The resistances 30 68 are connected in the rotor circuit of the motor. Here again, as before the automatic potentiometer starting circuit illustrated in Fig. 8 may be employed. In this case the relay 70 has its operating winding connected at one terminal by 35 wire 145 to one of the wires 135. The other terminal of this winding is connected by wire 146 to one of the contacts of the start switch 99 and is likewise connected to one contact of the third lowest pair of the relay. One contact of the 40 stop switch 98 is connected by wire 148 through the relay switch 97 and wire 149 to the other contact of the third lowest pair of relay 70. The other contacts of the switches 99 and 98 are connected to a common wire 147 to the other wire 45 135. One terminal of the grounded secondary of transformer 136 is connected to one terminal of the solenoid of relay 97 and to one contact of the lowest pair of relay 70. The other contact of this pair is connected to wire 150 which 50 connects the other terminal of the solenoid of relay 97 with the brush of ring 10. One terminal of the upper and lower resistances 68 is connected by the wires 151 to one contact of each of the two upper pairs of relay 70. The corresponding contacts of these pairs are connected by a common wire 152 to the remaining resistance 68.

In this arrangement the relative strength of the windings 22 and 97 is such that when switch 60 28 is opened the current flowing is not enough to operate the relay or enough to cause the brake coil 22 to exert any serious braking action on the cop spindle. When switch 61 is closed the primary of transformer 136 is energized and the 65 stator or field winding of motor 65 is energized. To start the apparatus switch 99 is closed which completes a circuit which may readily be followed to the solenoid of relay 70, energizing it and operating the relay. The operation of the relay establishes a holding circuit therefor through the third lowest pair of its contacts. This holding circuit is broken by opening stop switch 98 to stop the motor 65 by breaking the common connection across the ends of resistances 68 in the rotor 70 75 75

circuit. At the same time a more direct circuit from the secondary of transformer 136 through the lowest pair of contacts of relay 10 is made to the brake coil 22 causing it to prevent the cop 5 spindle from overrunning and directly short circuiting the winding of relay 97. When the apparatus is automatically stopped by the breaking of the tape, switch 28 closes, completing the circuit to the solenoid of relay 97 through wire 150 10 and hence breaking the holding circuit for relay 10 at relay 97. Here again the return of relay 10 to the deenergized position shown short circuits relay 97 and directly connects the cop spindle brake coil 22 to the secondary of transformer 136.

From the above description it will be apparent that this invention resides in certain principles of construction which may be embodied in other physical forms without departure from the scope 20 thereof. We do not, therefore desire to be strictly limited to the disclosure as given for purposes of illustration, but rather to the scope of the appended claims.

What we seek to secure by United States Letters 25 Patent is:

1. A serving head as described comprising a motor, a rotatable support driven by said motor, a cop spindle rotatably journaled on said support, a magnetic brake acting upon the cop spindle to 30 prevent rotation thereof on the support when energized, an energizing circuit for said brake including a control switch, means for biasing said switch to closed position, and means acting to oppose said biasing means to prevent closing of 35 said switch when a web is being fed from a cop on the cop spindle.

2. A serving head structure of the type described comprising a motor, a rotatable member driven by said motor, a cop spindle journaled on 40 said member for supporting a strand spool, and magnetic braking means secured to said member and rotated by it including a switch for controlling a circuit to energize said means when the strand breaks to prevent rotation of the cop spindle on said member.

3. A combination comprising a serving head including a cop spindle rotatably mounted thereon, an electric motor for driving the serving head, a magnetic brake positioned to act on the cop 50 spindle, a switch having an operating member engaging the cop spindle and normally held open when a web is being fed from the cop spindle, a circuit for said motor and magnetic brake including a control device controlled by said switch 55 whereby said motor is deenergized and the magnetic brake is energized when the web breaks.

4. An apparatus as described comprising a serving head having a cop spindle rotatably mounted thereon, said cop spindle being adapted 60 to support a strand spool, means for rotating the serving head, a magnet winding positioned to bring the cop spindle to a stop when energized and a switch engaging the cop spindle and held open by rotation thereof for completing a circuit to the winding when a strand fed from the spool breaks.

5. An apparatus as described comprising a serving head having a cop spindle rotatably mounted thereon, said cop spindle being adapted 70 to support a strand spool, means for rotating the serving head, a magnet winding positioned to bring the cop spindle to a stop when energized, a circuit for said winding and a switch in said circuit engaging the cop spindle and normally 75

held open when a strand is being fed from the strand spool.

6. In a structure as described the combination comprising a rotatable plate, a magnetizable cop spindle rotatably journaled on the plate, and a fixed magnet winding mounted adjacent the cop spindle and on said plate for bringing the cop spindle to a stop when energized. 5

7. In a structure as described the combination comprising a rotatable plate, a magnetizable cop 10 spindle rotatably journaled on the plate, a fixed magnet winding mounted adjacent the cop spindle for bringing the cop spindle to a stop when energized, a circuit for said winding, and a normally closed switch in said circuit and positioned 15 to engage the cop spindle so as to be held open by the feeding of a strand from the cop spindle.

8. In a structure as described the combination comprising a rotatable plate, a magnetizable cop spindle rotatably journaled on the plate, a fixed 20 magnet winding mounted adjacent the cop spindle for bringing the cop spindle to a stop when energized, a spring closed switch positioned to engage the cop spindle and normally held open against the closing action of the spring by the 25 feeding of a strand from the cop spindle, and a circuit including said winding and switch whereby the winding is energized when the strand breaks.

9. In a serving head of the type for wrapping 30 a web around a core and including a rotatable shaft having a cop spindle freely journaled thereon for supporting a web spool, the combination comprising a magnetizable core positioned adjacent the cop spindle, a magnetizing winding 35 therefor, a switch positioned engaged by the cop spindle and normally held open by the feed of a web from the spool on the spindle, and circuits including said switch and winding whereby the winding is energized when the web breaks. 40

10. A stopping mechanism for a serving head comprising in combination a motor driven serving head having a cop spindle rotatably mounted thereon, an energizing circuit for said motor, a switch in said circuit engaged by the cop spindle 45 and normally held open when a web is being fed therefrom, and means for closing the switch when the web breaks.

11. A stopping mechanism for a serving head comprising in combination a motor driven serving head having a cop spindle rotatably mounted thereon, a switch engaged by the cop spindle and normally held open when a web is being fed therefrom, means for closing the switch, a magnetic brake operating on the cop spindle and 55 circuits for said motor and brake controlled by said switch for causing deenergization of the motor and energization of the brake when the switch closes.

12. In a machine for applying a web in the 60 form of a spiral wrap around a longitudinally moving strand, the combination comprising a motor driven serving head, a motor generator connected to the serving head to operate it, energizing circuits for the serving head motor and the motor generator including starting resistances for the motor and the motor generator, and automatically operating time switches for gradually cutting resistances in to the rotor circuit of said 65 motor. 70

13. In a machine of the type described the combination comprising a serving head, an electric motor for operating the serving head, a generator connected thereto for supplying current 75

- to the serving head motor, a second motor for operating the generator, energizing circuits for said second motor including control devices, and means for automatically cutting resistances in 5 to the circuits of the second motor to bring it up to speed after initial energization.
14. In a machine for wrapping a web around a core, the combination comprising a serving head, an electric motor for operating the serving head, 10 a generator connected to said motor for energizing it, a second motor for operating the generator, energizing circuits for the second motor and said generator, including control devices, and means connected to the control devices for operating them to break the energizing circuits when the web breaks.
15. In a machine for wrapping a web around a core, the combination comprising a serving head, an electric motor for operating the serving head, 20 a generator connected to said motor for energizing it, a second motor for operating the generator, energizing circuits for the second motor and said generator including control devices, means connected to the control devices for operating them to break the energizing circuits when the web breaks, and a magnetic brake controlled by said control devices for bringing the serving head to a stop when the web breaks.
16. In a machine for wrapping a web around a core, a serving head having a freely rotatable web spool spindle mounted thereon, an electric motor for operating the serving head, a generator connected to said motor for energizing it, a second motor for operating the generator, energizing circuits for said second motor and generator including control devices, and means con- 30
- nected to the control devices for operating them to deenergize said second motor and said generator when the web breaks.
17. In a machine for wrapping a web around a core, a serving head having a freely rotatable web spool spindle mounted thereon, an electric motor for operating the serving head, a generator connected to said motor for energizing it, a second motor for operating the generator, energizing circuits for said second motor and generator including control devices, means connected to the control devices for operating them to deenergize said second motor and said generator when the web breaks, and magnetic braking means energized when the web breaks for preventing rotation of the spool spindle on the serving head. 10
18. A structure as described comprising a rotatable plate, a cop spindle rotatably mounted on said plate, a magnetizable member secured to said cop spindle, a magnetic brake positioned to magnetize said member, and means controlled by the cop spindle for energizing said brake when the web being fed from the cop spindle breaks. 15
19. In a serving head having a power driven shaft, a cop spindle freely journaled thereon and a magnetizable member carried by the spindle, the combination comprising a magnetizable core positioned adjacent the magnetizable member on the cop spindle, a winding for magnetizing the core, a circuit for said winding, and a switch in said circuit engaging the cop spindle for holding the circuit open at the switch when a strand is being fed from the cop spindle. 25
